UNITED STATES PATENT OFFICE.

LOUIS H. THULLEN, OF EDGEWOOD PARK, PENNSYLVANIA, ASSIGNOR TO THE UNION SWITCH & SIGNAL COMPANY, OF SWISSVALE, PENNSYLVANIA, A CORPORATION OF PENNSYLVANIA.

RELAY.

No. 868,232.

Specification of Letters Patent.

Patented Oct. 15, 1907.

Application filed April 30, 1907. Serial No. 371,162.

To all whom it may concern:

Be it known that I, LOUIS H. THULLEN, a citizen of the United States, residing at Edgewood Park, in the county of Allegheny and State of Pennsylvania, have 5 invented certain new and useful Improvements in Relays, of which the following is a specification.

This invention relates to relays and particularly to the insulating top which supports the electro magnet, contact posts, etc., and the object of the invention is to 10 provide a reinforced top which will better withstand strains without impairing its insulating qualities.

I will describe a relay embodying my invention and then point out the novel features in claims.

In the accompanying drawings: Figure 1 is a vertical 15 transverse section on the line 1—1 of Fig. 2, and Fig. 2 is a plan view partly in section on the line 2—2 of Fig. 1.

A is a base which may be of metal and will preferably be circular, and is provided with an annular rabbet *a* in its upper edge.

20 B is a cylindrical tube of glass or other transparent material, the lower end of which fits in the annular rabbet *a*, and a washer *b* is interposed between said lower end and the base.

The top consists of a metal plate C embedded in and 25 entirely inclosed by insulating material D. Or in other words the top consists of a plate of insulating material within which is a metal core. As shown, the metal plate C is of substantially the same diameter as the cylinder B, while the inclosing body of insulating 30 material is of greater diameter and is provided with a depending annular flange *d* which engages the outer surface of the cylinder B at its upper end. Preferably a washer *c* will be interposed between the upper end of the cylinder and the top.

35 The metal plate C is provided with a series of square openings *f* and the insulating material extends through these openings and form ties or bonds between the insulating material on the opposite surfaces of the plate C. A series of square recesses *g* are formed in the lower 40 surface of the insulating material of less size than the openings *f* in the plate C and opposite thereto. These

recesses are for the purpose of receiving the square portion *h* of the contact posts H and the cylindrical portion *h'* extends upwardly through the insulating material in the openings *f* and out beyond the top surface 45 of the insulating material.

By means of the construction illustrated and described, I provide an insulating top for the relay which will withstand greater strains than if formed entirely of insulating material, and one which is less liable to warp 50 or break. Furthermore the contact posts are completely insulated from each other and from the metal core of the top.

While I have shown the openings *f* and the recesses *g* square, it is obvious they may be of other angular 55 form or even round. I prefer, however, to make them angular, especially the recesses as any tendency of the posts to turn axially is thereby prevented.

It is not necessary to describe the other parts illustrated in the drawing as they are well known and form 60 no part of the present invention.

Having described the invention, I claim:

1. An insulating top for relays consisting of a metal plate having openings therein, and insulating material entirely inclosing said plate and filling said openings, and 65 said insulating material having recesses formed in one surface opposite said openings.

2. An insulating top for relays consisting of a metal plate having angular openings therein, and insulating material entirely inclosing said plate and filling said openings, and said insulating material having recesses formed 70 in one surface opposite said openings, said recesses being similar in outline to said openings but of smaller dimensions.

3. An insulating top for relays consisting of a metal plate having openings therein, and insulating material entirely inclosing the metal plate and filling said openings, and said top having a peripheral flange also of insulating material.

In testimony whereof I have signed my name to this 75 specification in the presence of two subscribed witnesses.

LOUIS H. THULLEN.
